C. J. BROWN.
ANTISLIPPING LADDER ATTACHMENT.
APPLICATION FILED FEB. 23, 1918.

1,304,018.

Patented May 20, 1919.

FIG. 4.

INVENTOR:
C. J. Brown.
BY his ATTORNEY:
A. M. Carlsen.

UNITED STATES PATENT OFFICE.

CHARLES J. BROWN, OF RIVER FALLS, WISCONSIN.

ANTISLIPPING LADDER ATTACHMENT.

1,304,018.

Specification of Letters Patent.

Patented May 20, 1919.

Application filed February 23, 1918. Serial No. 218,874.

To all whom it may concern:

Be it known that I, CHARLES J. BROWN, a citizen of the United States, residing at River Falls, in the county of St. Croix and

5 State of Wisconsin, have invented a new and useful Antislipping Ladder Attachment, of which the following is a specification.

My invention relates to ladders, and the object is to provide the lower end of a ladder with anti-skidding attachment or means which will effectively prevent slipping of the ladder on ice-covered or frozen ground and on boards used for supporting the ladder where the ground is loose or soft.

10 15 In the accompanying drawing, Figure 1 is an elevation of the lower portion of a ladder equipped with my invention. Fig. 2 is an enlarged left side view of the lower left corner of Fig. 1. Fig. 3 is a view of 20 the device as shown in Fig. 2 as viewed from the left and with the ground calk lowered. Fig. 4 is a bottom view of the metallic frame of the attachment.

25 Referring to the drawing by reference numerals, 5 designates the rails and 6 the rungs of a ladder. To the lower end of each rail I secure by a screw 7 the vertical flange 8 of an angle-plate 8-9, whose horizontal flange 9 is provided with a comparatively large aperture 10 (see Fig. 4). Held between the flange 9 and the bottom end or face of the rail is the flange 11 of a rubber cushion 12, which projects downward through and below the aperture 10. The 30 cushion is further held by a wood-screw 13 passed through the middle of it and into the end of the rail 5. The countersinking for the head of said screw is made so large as to serve as a suction cup which will aid 40 in holding the ladder stationary.

45 Formed upon the flange 8 is a wedge-shaped cam or incline 14, whose lower end forms a small upward shoulder 15 and a larger downward shoulder 16. 17 is a calk pivoted on a rivet 18, which is passed through the flange 8 and the rail as best shown at 19 to the left in Fig. 3. Said calk has a sharp point 17^a and a shoulder 17^b.

50 If the ladder is to be used on ordinary ground, 20, or upon a board covering soft ground, but especially if placed upon a finished floor, the calk 17 may be turned upward as shown in full lines in Fig. 2 and retained in that position by forcing it more or 55 less upon the incline 14, thus leaving the

ladder standing on the cushions 12, which will not injure the floor nor slip on smooth wood work of any kind. And if the ladder is placed upon frozen or ice covered ground, or upon a wet slippery supporting board 60 the calks are turned downward to the position shown in Figs. 1 and 3 or in dotted line in Fig. 2, with the shoulder 17^b engaging the shoulder 16 of the cam, whereby the calk is held firmly for engagement in the 65 surface supporting the ladder. The shoulder 15 on the cam is designed to support the calk in its upper position in the event that wear and tear should make it so loose on the pivot that the incline 14 will not engage 70 and hold it by friction.

What I claim is:—

1. A ladder attachment comprising two angular plates and means securing one flange of each plate in vertical position to 75 one side of each rail of the ladder near the bottom end thereof, the other flange of each plate extending horizontally underneath the end of the rail, a calk pivoted on the vertical flange and having a sharp end adapted 80 when in a downward position to engage in the surface that supports the ladder, means on the vertical flange for retaining the calk in engagement with said surface, and means on the same flange for holding the calk out 85 of such engagement.

2. The structure specified in claim 1, said means for holding the calk in engaged position consisting of a lug, and the means for holding the calk in disengaged position consisting of an inclined cam on the flange for 90 the calk to engage and be held by friction against said cam.

3. The structure specified in claim 2, said cam having near its highest point a lug by 95 which to positively stop the calk in case the latter should pass the position in which it was intended to be held by friction.

4. The structure specified in claim 1, said horizontal flange having an aperture, a rubber cushion held between said flange and the rail and having a portion projected downward through said aperture. 100

5. The structure specified in claim 4, said projected portion of the cushion having a 105 cavity acting as a suction cup to aid in holding the ladder stationary upon the surface supporting it.

In testimony whereof I affix my signature.
CHARLES J. BROWN.
